UNITED STATES PATENT OFFICE.

ANDERS MATHIAS RODBERG, OF TAMPA, FLORIDA.

MARINE STEAM-TURBINE.

1,353,360.

Specification of Letters Patent. Patented Sept. 21, 1920.

Application filed June 7, 1919. Serial No. 302,375.

To all whom it may concern:

Be it known that I, ANDERS MATHIAS RODBERG, a citizen of the United States, and a resident of Tampa, in the county of Hillsborough and State of Florida, have invented 5 a new and useful Improvement in Marine Steam-Turbines, of which the following is a specification.

My present invention relates generally to 10 steam turbines, and more particularly to a heavy duty reversible turbine for marine use and among its various objects, my invention aims to utilize the expansive and impact force of steam to a maximum degree 15 and with maximum efficiency and at the same time provide for ready reversibility and similar speeds and power in both ahead and astern duty.

My invention further aims to provide a 20 marine steam turbine of simple, substantial construction having the advantage of low initial cost and economical consumption and upkeep.

A still further object is the provision of a 25 marine steam turbine embodying a rotor of large diameter and consequently large rotating effect, producing maximum power at moderate speed so that it may be directly coupled without gearing.

30 A still further object is the provision of a marine steam turbine whose construction will economize floor space and maintain a considerable factor of safety since all moving parts may be cast in units without the 35 usual bracing and soldering of parts and since the rotor is full floating so as to eliminate bearing pressure.

The foregoing objects and others, together with the advantages and structural 40 details of my improvements will be thoroughly understood from the following description of its several specific parts, reference being made to the accompanying drawings, forming a part of this specification, 45 and wherein,

Figure 1 is a side view, partly in elevation and partly in section,

Fig. 2 is a side elevation complete,

Fig. 3 is an end elevation complete,

50 Fig. 4 is an end view partly in elevation and partly in section,

Fig. 5 is a vertical section through the upper or secondary steam chest, taken in the

plane of the final steam exhaust to the condenser,

Fig. 6 is a detail vertical section through the secondary steam valve, removed,

Fig. 7 is a bottom plan view thereof,

Fig. 8 is a top plan view of the secondary steam chest with the cap and valve removed,

Fig. 9 is a top plan view of the primary steam chest with its valve removed,

Fig. 10 is a vertical section through the primary steam valve removed,

Fig. 11 is a bottom plan view thereof,

Fig. 12 is a side view partly in elevation and partly in section of the primary steam chest and certain adjacent parts,

Fig. 13 is a side view, partly in elevation and partly in section, of a portion of the 70 rotor,

Fig. 14 is a plan view of a portion of the rotor,

Fig. 15 is a horizontal section through one of the peripheral impulse vanes,

Fig. 16 is a section through a portion of the rotor, and stator, taken radially of the former,

Fig. 17 is a section taken diametrically through a portion of the rotor and stator,

Fig. 18 is an enlarged section through one of the vane compartments at the lower portion of the stator with a vane therein,

Fig. 19 is an enlarged horizontal section through the intermediate portion of the 85 rotor, and

Fig. 20 is a plan view partly in elevation and partly in section of a portion of the rotor.

Referring now to these figures, my improved marine steam turbine comprises in general, a steam cylinder 25 which forms the stator and incloses a rotor 26 the latter of which extends from end to end of the cylinder and is fast upon the power shaft 27 journaled through the cylinder ends and also through bearings 28 of the supporting frame 29 within which the cylinder is disposed.

The upper portion of the casing 30 of the 100 cylinder 25 has an exhaust chamber 31 for expanded steam delivered from said chamber to the secondary steam chest 32 through a pipe 33, from which chest 32 expanded steam is fed to one end of the cylinder 25 through pipes 34, 35 for use as an impact

fluid injected, through the rotor secondary vanes, parallel to the shaft 27.

The steam chest 32 also has a final steam exhaust 36 from which steam is discharged 5 into a condenser as usual.

The secondary steam chest 32 is superposed upon the primary steam chest 37 which receives steam from the boiler through an inlet pipe 38 and from which 10 the steam, after utilization in connection with the peripheral primary vanes of the rotor, passes to the exhaust chamber. These several parts in their proper relation may be 15 readily seen in Figs. 1 to 4 inclusive and having thus given a very general survey, I will now proceed to take up the parts in detail following the general path of the steam in action.

The steam inlet pipe 38 as seen in Figs. 1 20 and 2 is preferably provided as shown in Fig. 2 with controlling valves 39, 40 and 41 for full speed, half speed and slow speed, and communicates with the interior of the primary steam chest through an opening 42 25 in the annular wall of the latter.

The primary steam chest is superposed directly upon the top of the cylinder casing 30 and has a flat base 43 which, as seen in Figs. 4, 9 and 12, has a series of openings, 44, 45, 46, 30 47, 48, 49, 50 and 51 respectively communicating with the upper ends of the primary steam channels 52, 53, 54, 55, 56, 57, 58 and 59 seen in a complete series in dotted lines in Fig. 9 and which extend downwardly 35 through the primary exhaust chamber in the cylinder casing 30 and communicate at their lower ends with the peripheries of the stages of the rotor as hereinafter described. It should be noted from Fig. 9 that the 40 above mentioned series of openings 44 to 51 inclusive are arranged in substantially circular form along with an exhaust opening 60 and that the steam channels progress along each side in gradually increased width 45 at their lower ends and gradually increasing in numbers of discharge apertures. For instance, as shown, channels 52 and 53 have single discharge apertures, channels 54 and 55 have each a pair of branches, channels 56 50 and 57 have three branches and channels 58 and 59 have four branches.

On a flat base 43 of the primary steam chest is a valve member 61 rotatable therein and having a series of cross channels communicating between lower openings 62, 63, 55 64, 65, 66, 67, 68 and 69 in the bottom surface seated flatwise on the base 43. These valve openings are arranged in circular form with an inlet opening 70 which extends vertically through the valve member and thus places either of the channel openings 44 or 45 in communication with the steam space of the valve chest, depending upon the particular position of the valve at 60 65 this time.

Thus with the valve inlet opening registered with channel opening 44, steam passes downwardly through channel 52 and around the rotor and then upwardly through channel 53, to valve opening 63 from which it 70 crosses to valve opening 62 and downwardly around the rotor through opening 46 and channel 54. This proceeds until the steam is finally discharged through the exhaust opening 60, and in each instance it will be 75 noted that the steam passes around the rotor in the same direction and its gradual expansion through the operation is taken care of by openings and channels of gradually increasing areas as shown and by gradually 80 increasing numbers of branches at the lower ends of the channels. Obviously if the valve 61 is partially rotated so that the inlet opening 70 registers with the channel opening 45, the same operation proceeds 85 although the steam is delivered in each instance at the relatively opposite side of the rotor.

Rotative adjustment of valve 61 is accomplished by means of a pair of links 71 and 90 72 pivotally connected thereto and to the ends of a walking beam lever 73 fulcrumed on the exterior of the steam chest 37 as most clearly seen in Figs. 3 and 9. One portion of lever 73 has a rack engaged by a gear 75 95 mounted on a controlling shaft 76 having a hand wheel 77 at its outer end. This shaft 76 has bearings in brackets 78 and 79, the latter of which as seen in Fig. 3 also supports the lower end of a vertical shaft 80 100 rigid with the lever 73 and forming the fulcrum thereof.

After its passage through the various channels controlled by the primary valve 61 and around the rotor as previously described, the steam is discharged through exhaust opening 60 into the exhaust chamber 31 and from said exhaust chamber through pipe 33 to the secondary valve chest 32 which latter has a horizontal flat partition 110 81 dividing the same into an upper steam chamber 82 and a lower exhaust chamber 83.

The partition 81 has a series of four openings 84, 85, 86 and 87, grouped around a central exhaust opening 88, and communicating with the upper, inner ends of the secondary steam pipes 34 and 35. On the partition 81 is a flatwise seated valve 89 seen in Figs. 6 and 7 in particular, having a lower cavity 90 and openings 91, 92, 93 and 94 so spaced as to bring openings 91 and 92 into registry with the partition openings 84 and 85 while partition openings 86 and 87 are communicated with the exhaust opening 88 by the exhaust channel 90. Likewise by shifting the valve 89 through a partial rotation, its openings 93 and 94 will be registered with the partition openings 86 and 87 when the channel 90 communicates the partition openings 84 and 85 with the 130

exhaust opening 88. Like the primary valve 61, the secondary valve 89 is shifted by links 95 which are journaled through the wall of the secondary steam chest and, as seen in Fig. 8, are connected to the ends of a walking beam lever 96 secured at an intermediate point to the upper end of the vertical shaft 74. Thus the secondary valve is actuated simultaneously with the primary valve when the turbine is reversed.

The steam passing outwardly through the exhaust opening 88 and through the final exhaust pipe 36 is, as usual, carried to a condenser (not shown).

The rotor 26 has a plurality of alined hubs 97, each with an annular blade ring 98, and a series of openings 99 around its axial shaft receiving bore 100. Connecting bolts 101 are extended through the openings 99 to connect the hub in contacting relation which leaves the series of blade rings 98 in spaced relation by reason of their reduced thickness as compared to the hubs, providing for the reception of the annular inwardly projecting fins 102 of the stator or cylinder 25.

As seen particularly in Figs. 16, 17 and 18, the stator or cylinder 25 has a plurality of annular channels 103, one around each annular series of fins 102 and is provided at its upper portion with apertures 104 communicating between these channels 103 and the exhaust chamber 31 as seen in Fig. 1.

The fins 102 of the stator are inclined as seen particularly in Fig. 19 and those portions of the blade rings 98 of the rotor co-extensive with these fins are also provided with fins or blades 107 inclined in opposition thereto, so that the steam discharged through the cylinder parallel to its axis, from the steam feeding rings 105 at the opposite ends of the cylinder, with which the lower ends of the secondary steam pipes 34 and 35 communicate, the steam passing from the feed rings 105 through nozzles 106 will act against the fins. In this way the impact force of the steam is utilized after the steam has expanded throughout the first stage of its use.

Between the channeled portions of the stator 25 are pockets receiving the peripheral portions of the blade rings 98 of the rotor, which peripheral portions carry annular series of spaced, peripherally open blades 108 plainly seen by reference to Figs. 13, 14 and 15, the blades of each outstanding series having concaved opposing faces and being connected and reinforced by median webs 109. These bladed peripheries of the rotor rings are under the influence of the steam fed through the primary feed channels 52 to 59 inclusive as seen in Fig. 9 and the steam thus acts in the first instance to propel the rotor like a belt or a series of belts on a pulley.

By reference again to Figs. 16, 17 and 18

it will be noted that the blade rings 98 of the rotor and the channeled adjacent portions of the stator have annular inclined meeting grooves 110 which function to prevent escape of steam and that other grooves 111 are also provided in these parts for the same purpose and for the further purpose, as shown, of communicating with the channels 103 so as to carry off, into the exhaust, any steam which does, as a matter of fact, escape past the grooves 110.

From the foregoing it is obvious that by turning on one or more of the steam controlling or inlet hand valves 39, 40 and 41, steam is admitted to the primary steam chest 37 and from there distributed through the primary valve 61 to the several primary feed channels 52 to 59 inclusive. The steam is thus forced around the rotor in successive rotation from end to end of the rotor and during its travel and expansion in this movement, acts on the peripheral blades 108. The steam then finds its way into exhaust chamber 31 and, along with any leaking steam, passes to the secondary steam chest 90. From this steam chest the partially expanded steam flows through either the pipes 34 or 35 to the respective feed ring 105, through the secondary valve 89, and is fed through the nozzles 106 and through the fins of the rotor rings and stator, finally discharging as above described.

It is evident that I am thus enabled to carry out the objects first above stated and that my invention provides a generally effective turbine of its class which is simple in construction, durable and economical.

I claim:—

1. In a marine turbine, a stator, a rotor therein having a hub, peripheral blades 105 and radial fins connecting the hub and blades, and means forming steam passages for successively feeding steam peripherally of the rotor to the said blades and through, and parallel to the axis of, the rotor against 110 said fins.

2. In a marine turbine, a stator, a rotor therein having a hub, peripheral blades and radial fins connecting the hub and blades, means for feeding steam peripherally of the rotor to the blades around the rotor, and means for feeding steam through, and parallel to the axis of, the rotor to said fins.

3. In a marine turbine, a stator, a rotor 120 therein having a hub, peripheral blades and radial fins connecting the hub and blades, means for feeding steam to the blades around the rotor, and means receiving said steam, after its passage around the 125 rotor, to feed the same through, and parallel to the axis of, the rotor to said fins.

4. In a marine turbine, a stator, a rotor 130 therein having a hub, peripheral blades and radial fins intermediate the hub and

blades, and means for feeding steam peripherally of the rotor against said blades and through the rotor parallel to its axis against said fins, including means for reversing the direction of movement of the steam.

5. In a marine turbine, a stator, a rotor therein having a hub, peripheral blades and radial fins intermediate the hub and 10 blades, and means for feeding steam peripherally of the rotor against said blades and through the rotor parallel to its axis against said fins, including valves for reversing the direction of steam flow.

15 6. In a marine turbine, a stator, a rotor therein having a hub, peripheral blades and fins connecting the hub with said blades, and means for successively feeding steam circumferentially around the rotor 20 for action against said blades and through the rotor parallel to the rotor axis for action against said fins.

7. In a marine turbine, a stator, a rotor therein having peripheral blades acted upon by steam moving circumferentially of the 25 rotor and also having fins inwardly of the blades acted upon by steam moving through, and parallel to the axis of, the rotor, and valved simultaneously reversible means for 30 controlling the direction of flow of steam to said rotor blades and fins.

8. In a marine turbine, a stator, a rotor therein having peripheral means acted upon by steam moving circumferentially of the 35 rotor and also having means inwardly of the blades acted upon by steam moving through, and parallel to the axis of, the rotor, and means for feeding steam to both of said rotor carried means including simultaneously reversible valves controlling the 40 direction of flow of the steam, for the purpose described.

9. In a marine turbine, a stator, a rotor therein having peripheral means acted upon by steam moving circumferentially of the 45 rotor and also having means inwardly of the blades acted upon by steam moving parallel to the axis of the rotor, reversible means for feeding steam circumferentially 50 around the rotor, and means receiving steam from said first-named feeding reversible means, for feeding the steam through, and parallel to the axis of, the rotor.

10. In a marine turbine, a stator, a rotor 55 therein having peripheral means acted upon by steam moving circumferentially of the rotor and also having means inwardly of the blades acted upon by steam moving parallel to the axis of the rotor, means for feeding steam circumferentially around the rotor, and means receiving steam from said first-named feeding means, for feeding the steam parallel to the axis of the rotor, each of said steam feeding means including a re-

versible valve for controlling the direction 65 of movement of the steam.

11. In a marine turbine, a stator, a rotor therein having peripheral means acted upon by steam moving circumferentially of the rotor and also having means inwardly of 70 the blades acted upon by steam moving parallel to the axis of the rotor, means for feeding steam circumferentially around the rotor, and means receiving steam from said first-named feeding means, for feeding the steam 75 parallel to the axis of the rotor, each of said steam feeding means including a reversing valve, and connections between said valves for effecting simultaneous reversal.

12. In a marine turbine, a stator having 80 a working cylinder and an exhaust chamber adjacent to the cylinder, a rotor operating in said cylinder and having peripheral blades and radial fins inwardly beyond the 85 blades, a primary steam chest, means forming steam passages between said primary steam chest and the periphery of the rotor for directing steam against the said blades, having an outlet into said exhaust chamber, a secondary steam chest receiving the steam 90 from said exhaust chamber, and means forming steam passages between the secondary steam chest and the rotor for directing steam parallel to the axis of the latter against said fins, having a final steam exhaust, as described.

13. In a marine turbine, a stator having a working cylinder and an exhaust chamber adjacent to the cylinder, a rotor operating in said cylinder and having peripheral 100 blades and radial fins inwardly beyond the blades, a primary steam chest, means forming steam passages between said primary steam chest and the periphery of the rotor for directing steam against the said blades, 105 having an outlet into said exhaust chamber, a secondary steam chest receiving the steam from said exhaust chamber, and means forming steam passages between the secondary steam chest and the rotor for directing steam parallel to the axis of the latter against said fins, having a final steam exhaust, and reversible valves in said steam chests for controlling the direction of flow 110 of the steam.

14. In a marine turbine, a stator having a working cylinder and an exhaust chamber adjacent to the cylinder, a rotor operating in said cylinder and having peripheral blades and radial fins inwardly beyond the 120 blades, a primary steam chest, means forming steam passages between said primary steam chest and the periphery of the rotor for directing steam against the said blades, having an outlet into said exhaust chamber, a secondary steam chest receiving the steam 125 from said exhaust chamber, and means forming steam passages between the sec-

ondary steam chest and the rotor for directing steam parallel to the axis of the latter against said fins, having a final steam exhaust, reversing valves in said steam chests, 5 and connections between said valves for effecting their simultaneous reversal.

15. In a marine turbine, a stator, a rotor therein having peripheral blades and fins inwardly beyond the blades, a primary steam chest having a steam inlet and outlet, 10 means forming steam channels between the said primary steam chest and the rotor for directing steam circumferentially around the latter against said blades, a secondary steam 15 chest receiving steam from the outlet of the primary steam chest and having a final steam exhaust, and means forming steam passages between said secondary steam chest and the rotor for directing steam parallel to the axis of the latter against said fins.

16. In a marine turbine, a stator, a rotor therein having peripheral blades and fins inwardly beyond the blades, a primary steam chest having a steam inlet and outlet, 20 means forming steam channels between the said primary steam chest and the rotor for directing steam circumferentially around the latter against said blades, a secondary steam chest receiving steam from the outlet of the primary steam chest and having a final steam exhaust, and means forming steam 25 passages between said secondary steam chest and the rotor for directing steam parallel to the axis of the latter against said fins, and a reversing valve in each of said steam chests.

17. In a marine turbine, a stator, a rotor therein having peripheral blades and fins 40 inwardly beyond the blades, a primary steam

chest having a steam inlet and outlet, means forming steam channels between the said primary steam chest and the rotor for directing steam circumferentially around the latter against said blades, a secondary steam 45 chest receiving steam from the outlet of the primary steam chest and having a final steam exhaust, and means forming steam passages between said secondary steam chest and the rotor for directing steam parallel to the axis 50 of the latter against said fins, a reversing valve in each of said steam chests, and connections between said valve for effecting their simultaneous reversal.

18. In a marine turbine, a stator having a working cylinder and an exhaust chamber adjacent to the cylinder, a rotor operating in said cylinder and having peripheral blades and radial fins inwardly beyond the blades, a primary steam chest, means forming steam passages between said primary steam chest and the periphery of the rotor for directing steam against the said blades, having an outlet into said exhaust chamber, a secondary steam chest receiving the steam 60 from said exhaust chamber, and means forming steam passages between the secondary steam chest and the rotor for directing steam parallel to the axis of the latter against said fins, having a final steam exhaust, said stator having pockets receiving the blades of the rotor, and provided in the walls of its said pockets with steam grooves and apertures leading from the grooves and opening into said exhaust chamber, and said 65 rotor having steam grooves in registry with the steam grooves of said pocket walls of the stator, all for the purpose described. 70 75

ANDERS MATHIAS RODBERG.
